UNITED STATES PATENT OFFICE.

HANNAH JACOBS AND HARRY JACOBS, OF BROOKLYN, NEW YORK.

HAIR DRYING AND WAVING APPARATUS.

Specification of Letters Patent. Patented Mar. 19, 1918.

1,260,266.

Application filed May 10, 1917. Serial No. 167,749.

To all whom it may concern:

Be it known that we, HANNAH JACOBS and HARRY JACOBS, citizens of the United States, and residents of Brooklyn, New York, in the 5 county of Kings and State of New York, have invented certain new and useful Improvements in Hair Drying and Waving Apparatus, of which the following is a specification.

10 Our invention relates to improvements in hair drying and waving apparatus and is in the nature of an improvement upon the device shown and described in our application filed on December 14, 1916, bearing Serial 15 Number 137,026, and allowed April 12, 1917.

We have found, in practice, that the operation of drying the hair is facilitated when the driven air is raised in temperature and the exhaust is drawn off by suitable means. 20 To provide an apparatus to accomplish this has been our object in this invention and how we accomplish this object will be hereinafter fully explained.

In the drawing Figure 1 is an elevation 25 and section of our device. Fig. 2 is a longitudinal sectional view of part of the apparatus which will be hereinafter designated as the drying unit; Fig. 3 is a cross section of same taken through line 3—3 looking in 30 the direction of the arrow X and Fig. 4 is a top view or plan of what we will hereinafter designate as the distributing crown and indicates a view looking in the direction of the arrow y of Fig. 1.

35 Referring to the parts, 1 designates an air duct through which heated air is forced and directed into the distributing rings 2, 3 and 4 of the distributing crown. The air is heated and forced through the said distributing crown by means of the air heating and 40 air driving units 5 and 6 which may be of any approved type.

The said rings 2, 3 and 4 are provided with outlet spouts 7 to which are connected, 45 by means of the flexible tubes 8, the drying units 9.

The said drying units 9, (see Figs. 2, and 3) are formed with an outer shell to one end of which the said flexible tube 8 is attached.

50 The opposite end of the said outer shell is partly closed by means of a head or end piece 10 which is preferably made of heat resisting material.

Concentrically located within the said

outer shell and secured to the said head 10 55 in line with the opening 11 is a tube 12, preferably of copper or other metal of high heat conductivity. The said tube 12 forms a drying chamber 15 and is provided with inlets 13 and outlets 14 which permit the 60 entrance and egress of air into and out of the said drying chamber 15. The said head 10 is provided with the cut out portions 16 in line with the outlets 14.

An outlet 17 is formed upon the outer 65 shell of the drying unit 9 and leads to the yoke and spout 18 to which there is connected a flexible tube 19 which in turn leads and is connected to an exhaust chamber 20 and exhaust duct 21. The said exhaust 70 chamber 20 may be provided with any suitable exhausting means.

The relative sizes of the exhausting member 20 and air heating and driving units 5 and 6 are not shown. These members are 75 located at some distance from the distributing crown and are diagrammatically shown.

The distributing crown is suitably located at about the angle indicated in Fig. 1 and is rigidly suspended from the ceiling or supported upon the floor by any approved 80 means.

In operation the person whose hair is to be operated upon is seated in a chair in the usual manner so that the head assumes the 85 position shown by the dotted lines in Fig. 1.

The hair is dampened and curled, in the usual manner, upon the stem which is inserted through the opening 11 into the drying chambers 15; cotton or other suitable fabric, or means, being employed to tightly close the opening 11 after the stem with the hair upon it has been inserted.

When all the drying units which are intended to be used are in place and connected the heating and driving members 5 and 6 are set in operation thereby driving the heated air through the duct 1 and distributing rings 2, 3 and 4, into the tubes 8, 90 through the drying units and out through the exhaust tubes 19 and exhausting members 20 and 21. Such of the spouts 7, in the distributing rings, as are not in use are closed by means of a suitable plug or cap.

100 It is obvious that we may employ various modifications without departing from the spirit of our invention. We do not there-

fore wish to be understood as limiting ourselves to the particular construction shown.

What we claim as our invention and desire to secure by Letters Patent, is:

- 5 1. In a hair drying and waving apparatus, a drying unit adapted to engage a winding stem having hair wound thereon, means for supplying a current of heated air to the said drying unit and means for exhausting the air from the said drying unit.
- 10 2. In a hair drying and waving apparatus, drying units adapted to engage winding stems having hair curled thereon, the said drying units having air inlets and air outlets formed thereon, means for forcing heated air under pressure into the said drying units and means for exhausting the air from the said drying units.
- 15 3. In a hair drying and waving apparatus, a double walled drying unit adapted to

engage a winding stem having hair wound thereon, means for supplying a current of heated air to the said drying unit and means for permitting the egress of the air from the said drying unit.

25 4. In a hair drying and waving apparatus, a plurality of double walled drying units adapted to engage winding stems having hair wound thereon, means for supplying currents of heated air to the said drying units and means for exhausting the air from the said drying units.

Signed at New York, in the county of Kings and State of New York, this 9th day of May, A. D. 1917.

HANNAH JACOBS.
HARRY JACOBS.
